UNITED STATES PATENT OFFICE.

NATHAN M. LOWER AND EDWIN ARCHER TURNER, OF PITTSBURGH, PENNSYLVANIA,
ASSIGNORS, BY MESNE ASSIGNMENTS, TO THE STANDARD STOKER COMPANY, INC.,
OF NEW YORK, N. Y., A CORPORATION OF DELAWARE.

LOCOMOTIVE AND STOKER THEREFOR.

Application filed May 25, 1926. Serial No. 111,550.

The invention relates to locomotive stokers of the scatterfeed type, in which the fuel is introduced above the level of the fire bed and is scattered thereover, as by means of steam jets. More specifically it relates to the type of stokers in which the fuel is delivered into the fire-box through an aperture in the back-head immediately above the level of the grates, and is directed upwardly into the zone of action of the steam jet.

Among the objects sought and attained by the invention are simplicity of construction and durability.

Preferred embodiments of the invention are hereinafter described, and are illustrated in the accompanying drawings, in which

Fig. 1 is a detail vertical central longitudinal section of the rear portion of a fire-box, cab, and forward portion of the stoker mechanism;

Figs. 2 and 3 are detail plan sections, respectively, on the lines 2-2 and 3-3 of Fig. 1;

Fig. 4 is a view similar to Fig. 1, showing a modified form of construction;

Fig. 5 is a detail plan section on the line 5-5 of Fig. 4;

Fig. 6 is a view similar to Fig. 1, showing a further modification;

Fig. 7 is a detail section on line 7-7 of Fig. 6;

Fig. 8 is a view similar to Fig. 6, showing a further modification; and

Fig. 9 is a detail section on the line 9-9 of Fig. 8.

The back-head of a fire-box is represented at 10, and its grate at 11. The cab floor or deck is shown at 12. An aperture 13 is formed in the back-head 10 immediately above the level 40 of the grates 11, and preferably under the hand firing door opening 14. A fuel delivery conduit 15, within which is housed a fuel advancing screw 16, projects loosely into the aperture 13.

A hollow U-shaped approximately vertical wall 17 is located within the fire-box and encloses the aperture 13 and the delivery end of the conduit 15, and encroaches but slightly on the grate area. The chamber of this wall is 50 in communication with the chamber of the back-head, as shown at 18, 18, to permit the circulation of water through it. The wall extends downwardly below the surface of the grates 11 a sufficient distance to permit the ac-

cumulation of sediment below the combustion 55 zone. The top 19 of the wall 17 is preferably flat.

Within the space inclosed by the wall 17 is fitted a casting 20, having the general shape of half of a bowl provided at its top margin 60 with a flat flange 21, which rests upon the top 19 of the wall 17, and along its outer face with a vertical web 24 which rests upon the inner face of the wall 17. The side of the bowl adjacent the back-head 10 is omitted or apertured to permit the delivery of fuel from the conduit 15. The curved wall of the bowl guides the fuel upwardly to its top, where it comes under the influence of steam jets issuing from a nozzle 22 secured to the back-head 70 10 and supplied with steam through suitable pipes, as indicated at 23. Preferably the nozzle 22 is divided into a plurality of chambers, as indicated by dotted lines in Fig. 2, separate steam leads communicating with 75 each of the chambers, thereby permitting the control of the jets for the purpose of trimming the fire.

The conduit 15 being supplied with fuel from the bin of the tender, and the screw 16 80 being driven by suitable means, as is common in devices of this character, the fuel is delivered into the bowl 20 and forced upwardly therethrough and is scattered by the steam jets, the flange 21 serving as a guide table 85 to facilitate its distribution. In the performance of this latter function the flange 21 is in effect the top of the wall 17, and serves as a reinforcement thereof to take the wear incident to the friction of the fuel.

The wall 17 is as effectually protected from the heat as is the back-head 10, as water will circulate freely through it, and the bowl 20 is 90 equally well protected. Should the flange 21 be eaten away by the heat, the bowl will, nevertheless, be retained in its place by engagement of the flange 24 with the wall 17 and of the rear margin of the bowl with the back-head, and the stoker will function equally well.

In the construction shown in Figs. 4 and 5 a wall 25 takes the place of the wall 17 in the construction already described, and differs therefrom in certain details. From the juncture with the backhead 10 the bottom 105 of the wall 25 inclines upwardly as shown at 26, to the central portion of its forward side, thereby preventing the accumulation of sedi-

ment within the wall, causing it all to descend into the mud ring of the backhead. The top margin of the wall 25 inclines downwardly, as indicated at 27, from its juncture with the 5 backhead, to the center of its forward portion, thereby preventing the accumulation of steam which may occur where a steaming chamber, entirely filled with water, is provided with a flat cover plate.

10 As it is desirable to provide a substantially level surface over which the fuel may be driven by the steam jets, the bowl 20 is of the same form as shown in Fig. 1, except that the forward portion of its flange 21 is provided with one or more depending flanges 28 which rest upon the top of the wall 25. While this form of construction of the bowl deprives its flange to some extent of the protection from heat derived from the circulation 15 of water through the wall 25, it is protected by air currents entering through the open end of the chamber enclosed by the wall 25 and passing into the firebox between the flange 21 and the top of the wall.

20 Where this form of wall is used, special 25 grate bars are provided to prevent the fuel from entering below it. To this end there is shown a grate bar 29 at each side of the wall structure, the inner end of the bar being inclined upwardly as indicated at 30, the upper end of the inclined portion meeting the side portion of the wall. The next pair 30 of grate bars 31 are also of special form, their inner ends being inclined upwardly 35 and backwardly as indicated at 32 to meet the bottom of the forward portion of the wall 25. These special grate bars are controlled by a lever 33 independently of the lever for actuating the remainder of the 40 grate.

45 In the construction illustrated in Figs. 6 to 9 a hollow wall 34 corresponding in its principal function to the walls 17 and 25, has its ends spaced from the back head 10, and connected therewith by short nipples 35, 35 at its top, and a pair of similar nipples, as 36, only one of which appears, adjacent its lower margin. The bottom of the wall 34 is located at, or, if desired, somewhat above the upper 50 surface of the grate, and is provided with a blow-off aperture as shown at 37, closed by means of a plug 38, through which sediment may be drained off and the chamber of the wall flushed.

55 The bowl 20 as in the forms already described may be present and prevents the fuel from escaping laterally from the chamber inclosed by the wall 34.

60 An inclined grate bar 39 is preferably located adjacent the outer surface of the wall 34 and prevents the heating of the lower portion of this wall to such an extent that should there be within it an accumulation of sediment it will not be baked. This grate bar 65 not only prevents the burning fuel from com-

ing directly in contact with the lower part of the wall, but also provides for the cooling of the latter by the admission of air immediately in its vicinity.

The invention is susceptible of embodiment 70 in various forms in addition to those shown and described. The manner of delivery of the fuel into the chamber enclosed by the wall located within the firebox may be varied and the bowl 20 may be omitted if desired. 75

We claim as our invention:

1. In a locomotive fire-box, a hollow back-head having an aperture adjacent the grate, a fuel delivering conduit discharging through such aperture, a hollow upstanding 80 U-shaped wall inclosing the aperture, its chamber being in communication with the chamber of the back-head, the chamber enclosed by the wall being closed at its bottom, and means above the wall for projecting fuel 85 thereover upon the grate.

2. In a locomotive fire-box, a hollow back-head having an aperture adjacent the grate, a fuel delivering conduit discharging through such aperture, an upstanding hollow 90 U-shaped wall inclosing the aperture, its chamber being in communication with the chamber of the back-head, a bowl-shaped element fitting within the space inclosed by the wall and being open to the conduit, and means 95 above the wall for projecting fuel thereover upon the grate.

3. In a locomotive fire-box, a hollow back-head having an aperture adjacent the grate, a fuel delivering conduit discharging 100 through such aperture, an upstanding hollow U-shaped wall inclosing the aperture, its chamber being in communication with the chamber of the back-head, a bowl-shaped element fitting within the space inclosed by the 105 wall and being open to the conduit and having an outstanding flange resting upon the top of the wall, and means above the wall for projecting fuel thereover upon the grate.

4. In a locomotive fire-box, a hollow back-head having an aperture adjacent the grate, a fuel delivering conduit discharging through such aperture, a hollow upstanding U-shaped wall inclosing the aperture, its chamber being in communication with the 115 chamber of the back-head, the lower end of the wall extending below the grate surface, the chamber enclosed by the wall being closed at its bottom, and means above the wall for projecting fuel thereover upon the grate. 120

5. In combination, a fire-box having a fuel-receiving aperture in the lower portion of its backhead, a water-cooled wall within the fire-box facing the aperture, extending above the level of the fire bed on the grate and forming a guide for the entering fuel, and means for scattering the fuel over the wall. 125

6. In combination, a fire-box having a hollow back-head, a hollow U-shaped wall within the fire-box and having its ends adja- 130

cent to and in communication with the back-head thereof, a closure for the bottom of the chamber enclosed by the wall, means for delivering fuel into such chamber, and means 5 for distributing fuel therefrom upon the grate of the fire-box.

7. In combination, a fire-box having a hollow back-head, a hollow U-shaped wall within the fire-box and having its ends adjacent to and in communication with the back-head thereof, the bottom of the wall being inclined upwardly from its ends, means for delivering fuel into the chamber enclosed by the wall, and means for preventing the fuel from 10 dropping from the chamber enclosed by the wall and means for discharging fuel therefrom upon the grate of the fire-box.

8. In combination, a fire-box having a hollow back-head, a hollow U-shaped wall within the fire-box and having its ends adjacent to and in communication with the back-head thereof, the bottom of the wall being above the grate, a normally inclined grate bar facing the space below the wall, means for 20 delivering fuel into the chamber enclosed by the wall, and means for discharging fuel therefrom upon the grate of the fire-box.

9. In combination, a fire-box having a hollow back-head, a hollow U-shaped wall within the fire-box, extending above the bevel of the fire bed on the grate and having its ends adjacent to and in communication with the back-head thereof, the top of the wall being inclined downwardly from its ends, means 30 for delivering fuel into the chamber enclosed by the wall such chamber being closed at its bottom, and means for distributing fuel therefrom upon the grate of the fire-box.

10. In combination, a fire-box having a hollow back-head, a hollow U-shaped wall within the fire-box and having its ends adjacent to and in communication with the back-head thereof, the top of the wall being inclined downwardly from its ends, a bowl within 40 the chamber enclosed within the wall and having an approximately horizontal flange overlying the top of the wall, means for delivering fuel into the chamber enclosed by the wall, and means for discharging fuel 45 therefrom upon the grate of the fire-box.

11. In combination, a fire-box having a

hollow back-head, a hollow U-shaped wall within the fire-box, its ends being adjacent to the back-head thereof, tubes connecting the chamber of the wall with the chamber of the back-head, the chamber enclosed by the wall being closed at its bottom, means for delivering fuel into such chamber, and means for discharging fuel therefrom over the grate of the fire-box. 55

12. In combination, a fire-box having a hollow back-head, a hollow U-shaped wall within the fire-box, its ends being adjacent to the back-head thereof, tubes connecting the upper and lower portions of the chamber of the wall with the chamber of the back-head, means for delivering fuel into the chamber enclosed by the wall such chamber being closed at its bottom, and means for discharging fuel 60 therefrom over the grate of the fire-box. 70

13. In combination, a fire-box having a hollow back-head, a hollow upstanding U-shaped wall within the fire-box, the chamber of the wall being in communication with the chamber of the back-head of the fire-box and having a drain opening in its bottom, means for delivering fuel into the chamber enclosed by the wall such chamber being closed at its bottom, and means for discharging fuel therefrom upon the grate of the fire-box. 75

14. In combination, a boiler, a fire-box having a back-head, a hollow U-shaped wall within the fire-box having its ends adjacent to the back-head, connection between the interiors of the wall and of the boiler, the chamber enclosed by the wall being closed at its bottom, means for delivering fuel into such chamber, and means for distributing fuel from such chamber over the grate of the fire-box. 85

15. In combination, a furnace having a grate and an upstanding wall, an upwardly inclined and upwardly opening fuel conduit entering the fire-box through the wall, means for advancing fuel through the conduit, means for scattering fuel delivered by the conduit in aerial paths on the grate, and a water cooled shield for protecting the conduit within the firebox. 95

In testimony whereof we affix our signatures.

NATHAN M. LOWER.
E. ARCHER TURNER.
